UNITED STATES PATENT OFFICE

CHARLES W. MORDEN, OF PORTLAND, OREGON

SMOKER'S DESK STAND

Application filed February 16, 1929. Serial No. 340,361.

My invention has for its purpose the providing of a neat and convenient smoker's desk stand in which to dispose of the ashes, burnt matches, butts and stubs of cigars and 5 cigarettes.

The commonly employed ordinary ash tray soon becomes cluttered up and then has an unsightly appearance; and the discarded butts and stubs frequently continue to burn 10 for a long time, and emit an offensive odor. To eliminate such undesirable conditions is the object of my invention.

My invention provides a smoker's desk stand comprising a hollow body which in itself may serve as the ash receiver, or for 15 convenience may be provided with a removable receptacle to serve that purpose.

The open top of the body is covered, in 20 part, with cover pieces the latter arranged to provide an opening between them, which is provided with closure means in order to conceal the contents of the ash receiver when not in use.

Preferably the body is made elongate, and 25 the opening of the cover, or top, is located intermediate the ends of, and is of lesser length than that of the body, so that the contents of the ash receiver are always more or less concealed by the top or cover, even with the 30 closure element of the opening thereof open.

The closure element of the opening of the 35 top or cover when closed further functions to smother and extinguish the lighted stubs and butts of cigars and cigarettes thrown into the receiver, and prevents their continuing to burn for any length of time.

A further object of my invention is to 40 provide a closure element, for the open top of my stand, consisting of two companion leaves, which in their open position constitute flaring extensions to the sides of the open top of the body.

A further object of my invention is to 45 provide in combination with the said leaves, means operable by the pressure of the finger for throwing said leaves open, for example, a push-button projecting above the top or cover, whereby the leaves of said closure element will be opened outwardly, quickly and

simultaneously without touching the same with the fingers.

A further object of my invention is to provide the top of the stand with a longitudinally recessed holder for the cigar or cigarette with the bottom of the recess located in a plane below that touched by the tops of the said leaves when opened; and said holder further arranged so that the burning end of the cigar or cigarette will be 55 projected over the opening into the ash receiver. Thus, the burning end will lie between the said opened, flaring leaves; and, furthermore, due to the lateral flare of said leaves when opened, a wider space is provided into which the ashes from the cigar or cigarette may be knocked off.

A further object of my invention is so to arrange the leaves of the closure element that those surfaces of the leaves which are 60 exposed when the leaves are opened, and with which the burning end of the cigar or cigarette may come into contact, thus soiling said surfaces, will be turned under and concealed from view when said leaves are closed; 65 thereby keeping clean and slightly the exposed surfaces of said leaves, when my stand is not in use.

The features above mentioned, and other incidental features of my invention will hereinafter be fully described with reference to the accompanying drawings.

In the drawings:

Fig. 1 is a perspective elevation of my desk stand in its preferred form:

Fig. 2 is a longitudinal, vertical section of my desk stand, as shown by Fig. 1, the section being taken close to the inner wall of the body of the desk stand;

Fig. 2a relates to Fig. 2 and shows in dotted outline a side elevation of the cover of my desk stand removed;

Fig. 3 is a cross section on the lines 3—3 of Fig. 2 but on a larger scale than the latter; and Fig. 4 is a similar partial cross section taken on the same line. These two views illustrate the operation of the hinged-leaves, constituting the closure element of the opening in the top of the cover. This figure further illustrates the means provided 100

for imposing a slight yielding resistance to the movement of the said hinged-leaves; and further illustrates diagrammatically, the operation of the means provided for throwing said leaves into open position without touching the same.

Fig. 5 is a side elevation, partly in section, illustrating a modified type of my desk stand. In this case the stand contains an ash receptacle which is removable through the base of the stand without disturbing the top of the stand; and

Figs. 6 to 11a inclusive, show parts and fragmentary details of construction employed when making my desk stand in the form illustrated by Fig. 5; the details shown by Figs. 9 to 11 inclusive being also embodied in that type of desk stand represented by Fig. 1.

Describing first Figs. 1 and 2: On the base *a* is removably mounted an ash receptacle *b*, secured in place by bolts and nuts *c*. The end walls of the ash receptacle are provided with resilient members *d* turned outward and down to provide a frictional holding means for the removable cover of this type of my desk stand. The cover consists of two pieces *e* and *e'*, of which Fig. 9 shows a perspective view looking at the under side of the piece *e*. These cover pieces are secured to the sidewalls of the cover. The interior opposed faces *f*, *f'* of the pieces *e*, *e'* are each provided with hinge sockets *g*, *g'* in which to receive the stub hinged-pins *h*, *h'* of the leaf *i*, and *h*', *h'* of the leaf *i'*. See the details of the latter in Figs. 10 and 10a.

As shown by Fig. 3 the leaves *i* and *i'* are of the same construction, each comprising perpendicular exterior ribs *j* and *j'* along its inner edge, such ribs being reduced in height towards one end so that when the leaves are closed as shown in Figs. 1 and 2, the rib *j* of the leaf *i* will project over the lower end of the rib *j'* of the leaf *i'*. Hence when the said leaves are in their closed positions, with the ribs *j*, *j'* in abutment, the projecting portions of said ribs will be adapted to permit the leaves to be separated by opposed pressure of two fingers of the hand.

In order to restrain the inadvertent movement of the leaves from the position in which manually placed, I employ the following devices: Resilient, yielding resistance plates *k* and *k*3 are secured to the under sides of the end of the cover pieces *e*, *e'*. These plates are provided with lips *k*2 and *k*4, respectively, at one end, and the plate *k* is further provided at the opposite end with a slotted lip *k'*. The actions of these resistance plates are illustrated by Figs. 3 and 4. As shown in Fig. 3 the leaves *i*, *i'* are closed, and the flat under surfaces of the said leaves are pressed against the lip *k'* by the resistance plate and thereby yieldingly held in their closed posi-

tion; and when the hinged-leaves are thrown into open position, as shown in Fig. 4, the pressure of the rib *k'* of the resistance plates *k* again serves to restrain the leaves *i*, *i'* in their open position by contact with the edges 70

In case it be preferred that my desk stand embody means for throwing the hinged-leaves *i*, *i'* into open position without touching the same with the hand, such action may be conveniently provided for as follows: A lever *m*, see Fig. 11a, has at one end a tongue *m'* and at its opposite end a rib *m*2. The tongue *m'* is inserted in the slot of the rib *k'* of the resistance plate *k* carried by the cover piece *e*, and the lever *m* fulcrums on said rib *k'* of this resistance plate. 75

A push-button *n* is secured to the tongue *m'* of the lever *m*. By depressing the said push-button the lever *m* is tilted thereby bringing its rib *m*2 into contact with the under side of the leaves *i*, *i'* and forcing them open as indicated in Fig. 4. Such action is to be accomplished by a sudden pressure of the push-button *n*, and as a result the rib *m*2 of the lever *m* will throw the leaves *i*, *i'* into their fully open position, as they are shown in full outline in Fig. 4; the action of their being so thrown open being illustrated by the dotted outline in Fig. 4 and the associated arrows. 80

The lever *m* and the push-button *n* thereof are held in the positions shown in Figs. 2 and 5 by the lip *m*2 of said lever bearing against the under sides of the hinged-leaves *i*, *i'*, when the latter are closed. See Fig. 3. When said hinged-leaves are thrown open, as shown by Fig. 4, then the expansion spring *n*' mounted on the push-button *n* under the cover piece *e* functions to tilt the lever *m*, see Fig. 6, thus holding said push-button depressed so that it will not interfere with the cigar or cigarette placed in the recess of the cover piece *e*. 90

Those faces of the leaves *i*, *i'* which are exposed to the burning end of the cigar or cigarette, may be protected by a covering of glass or other suitable material, as designated by *o* in Figs. 10, 10a and 10b. 105

Preferably, I make my stand of elongate form, and make the opening in the top thereof of lesser length than the full length of the stand; preferably locating such opening in the middle of the top. In that way the ash receiver of my stand will always be more or less concealed, even though the leaves are open as when my stand is in use. 110

In order to provide for the convenient holding of a cigar or cigarette on the cover, and with the burning end located over the opening in the top leading into the ash receiver, I provide the portions *e*, *e'* with longitudinal recesses *p*; and in order to bring the burning end of the cigar or cigarette within the sides of the leaves *i*, *i'* in their open posi- 120

tion, I locate the bottom of such recess in a plane below that touched by the tops of said leaves when open.

By reason of the outward inclination of the leaves *i* " when in open position, they constitute, in such position, flaring extensions to the tops of the sides, of the opening in the cover into the ash receiver. This arrangement further assures that the surfaces exposed when the leaves are open and liable to become tarnished, or otherwise more or less disfigured, by their proximity to the burning end of the cigar or cigarette, that when the leaves are closed, such tarnished surfaces will be turned under and thus concealed from view.

The construction of my desk stand as illustrated by Fig. 5, and the specific details, is in the main, similar to that illustrated by Figs. 1 and 2 with only these differences. The base *q* has a central rectangular portion cut away so as to admit of the insertion and removal of the receptacle *r* through the bottom of the base. In this type the cover pieces *e2* and *e3* are mounted on the side walls *x* of the cover, and screws *t* are inserted through the bottom of the base at each end and threaded into said cover pieces *e2*, *e3*, respectively, to hold the parts together.

On the head of the screw *t* is mounted a locking disc *u* having a straight side *u'*. Thus when this disc is arranged as shown in Figs. 6 and 8, the ash receptacle *r* may be inserted or removed from the stand, but when the locking disc *u* is arranged as shown in Fig. 5, said receptacle is held in place.

In order to prevent the locking disc *u* from becoming inadvertently arranged so as to permit the inadvertent dropping of the ash receptacle out of place, I provide a spring washer *v* inserted between the locking disc *u* and the portion *q'* of the base, where the latter is recessed to receive the screws *t* and the locking disc *u*.

In order to accommodate the movement of the operating parts relating to the leaves of the closure element of my desk stand, I provide the side walls of the ash receptacle with recesses *w*.

I claim:

1. A desk stand of the character described comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body and said leaves formed along their longitudinal inner edges with perpendicular exterior ribs abutting when said leaves are closed, with portions of each of said ribs exposed clear of the other when in abutment.

2. A desk stand of the character described

comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, said leaves formed along their longitudinal inner edges with perpendicular exterior ribs abutting when said leaves are closed, with portions of each of said ribs exposed clear of the other when in abutment and the top of the body provided adjacent its said opening with longitudinally recessed holders, the bottoms of the recesses being located in a plane below that touched by the tops of said closure leaves when open.

3. A desk stand of the character described comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, said leaves formed along their longitudinal inner edges with perpendicular exterior ribs abutting when said leaves are closed, with portions of each of said ribs exposed clear of the other when in abutment, the top of the body provided adjacent its said opening with longitudinally recessed holders and resilient elements carried by the underside of said top adapted to bear against the undersides of said closure leaves adjacent their longitudinal axis, whereby a slight yielding resistance is imposed to the movement of said closure leaves.

4. A desk stand of the character described comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, the top of the body provided adjacent its said opening with longitudinally recessed holders, the bottoms of the recesses being located in a plane below that touched by the tops of said closure leaves when open, resilient elements carried by the underside of said top, adapted to bear against the undersides of said closure leaves adjacent their longitudinal axis, whereby a slight yielding resistance is imposed to the movement of said closure leaves, an arm pivotally mounted on the underside of the said top, adapted to bear at one end adjacent the underside of said leaves when closed and connected at its other end to a spring controlled button projecting through the top, whereby manual pressure on the button will open said leaves simultaneously.

5. A desk stand of the character described

comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, an arm pivotally mounted on the underside of the said top, adapted to bear at one end adjacent the underside of said leaves when closed and connected at its other end to a spring controlled button projecting through the top, whereby manual pressure on the button will open said leaves simultaneously.

6. A desk stand of the character described comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, said leaves formed along their longitudinal inner edges with perpendicular exterior ribs abutting when said leaves are closed, with portions of each of said ribs exposed clear of the other when in abutment and resilient elements carried by the underside of said top, adapted to bear against the undersides of said closure leaves adjacent their longitudinal axis, whereby a slight yielding resistance is imposed to the movement of said closure leaves.

35 7. A desk stand of the character described comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, the top of the body provided adjacent its said opening with longitudinally recessed holders, the bottoms of the recesses being located in a plane below that touched by the tops of said closure leaves when open.

8. A desk stand of the character described comprising an elongate, hollow, body provided with an opening at the top, intermediate its ends, a closure element for said opening composed of companion leaves hinged on their longitudinal axis at their outer edges and adapted when opened to provide flaring extensions to the tops of the sides of the body, resilient elements carried by the underside of said top, adapted to bear against the undersides of said closure leaves adjacent their longitudinal axis whereby a slight yielding resistance is imposed to the movement of said closure leaves.

CHARLES W. MORDEN.
